UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed August 5, 1921. Serial No. 489,980.

To all whom it may concern:

Be it known that I, BURNHAM C. STICKNEY, a citizen of the United States, residing in Elizabeth, in the county of Union and State of New Jersey, have invented certain new and useful Improvements in Typewriting Machines, of which the following is a specification.

This invention relates to mechanism of the continuous billing or so-called fan-fold type, such as shown in the patent to Wernery & Smith, No. 1,132,055, granted March 16, 1915, and is herein disclosed as applied to a bookkeeping machine of the Underwood-Hanson type.

Heretofore, it has been impracticable to use a carbon-carrier and other features of the continuous billing or fan-fold type of mechanism on the bookkeeping machine of the type referred to, since the denomination-selecting mechanism at the rear of the last-mentioned machine necessitates the positioning of the extension or track for the carbon-carrier at such a height above the normal position of the platen that the latter cannot be lifted sufficiently by the usual mechanism to enable sufficient straightening of the web to permit the withdrawal by the carbon-carrier of the carbon-sheets attached thereto. Further difficulties also arose due to the fact that the forward end of the track would interfere with the adjustment of the denomination-selector at different positions along the carriage and also with the positioning of the tabulator-stops on the carriage. It will be evident that the difficulty found in adjusting the tabulator-stops on the bookkeeping machine equipped with fan-fold mechanism also exists in the usual typewriting machine of the continuous billing or fan-fold type.

According to one form of the invention, the excessive bending of the webs over the guide at the front end of the track located above the denomination-selecting mechanism is substantially avoided, by supporting the carriage extension or track in an inclined position. It will be seen that by giving the track a suitable inclination, the bend in the webs over the forward end of the track may be sufficiently diminished or even eliminated in straightening the webs when the platen is in raised position.

In order to render the back of the bookkeeping machine accessible for adjusting the

selector-dogs and tabulator-stops, the fan-fold extension or track is supported on a rear rail so that it may be swung about the same to raise the forward end of the extension from engagement with the rear of the carriage on which it normally rests. To limit the upward movement of the extension and hold it in raised position, when desired, provision may be made of suitable means, such as a toggle-device, which may be utilized to hold the extension in raised position, the toggle being collapsible to enable the return of the extension to its normal position.

Due to the normal inclination of the carbon-carrier and the variation in such inclination in swinging the track about the rear rail, the carrier tends to slide along the track. To prevent such accidental movement of the carbon-carrier, provision may be made of suitable braking means which, while permitting manual movement of the carrier, will prevent accidental movement.

Usually the rail on which the rear of the carbon-carrier track travels is supported by a frame connected to the back of the typewriter frame and resting directly on the same surface as the typewriter. Inasmuch as the typewriter of the bookkeeping machine rests upon the computer casing and the latter is usually mounted on a stand, it is impracticable to support the rear rail in the usual manner, since the top of the computer casing is only of sufficient size to receive the frame of the typewriter proper. It has been found advantageous, therefore, to support the rear rail for the carbon-carrier extension upon brackets secured to the rear of the typewriter frame.

Other features and advantages will hereinafter appear.

In the accompanying drawings,

Figure 1 is a diagrammatic side view showing the carbon-carrier positioned at the rear and the platen in position to receive typing thereon.

Figure 2 is a plan view of the structure shown in Figure 1.

Figure 3 is a view similar to Figure 1 but with the platen raised and the web straightened, the track for the carbon-carrier being shown in raised position in dot-and-dash lines.

Upon depression of the keys (not shown) of a typewriter forming part of a bookkeeping machine of the Underwood-Hanson type,

type-bars 11 are swung upwardly and rearwardly to cause types 12 thereon to engage a cylindrical platen 13, mounted on an axle 14 journaled in a carriage 15, which is supported for sliding movement transversely of the typewriter by means including a rear rail 16 fixed on the typewriter frame 17. Each type-bar in its effective movement actuates the usual escapement mechanism 10 (not shown) and effects a letter-feeding movement of the carriage.

As is usual in bookkeeping machines of the type referred to the frame 17 of the typewriter is set on the casing 18 of the computing mechanism, and provision is made of means whereby the letter-feeding movement of the carriage will effect denomination-selecting for the computing mechanism. To this end, provision is made of brackets 20 19 extending rearwardly from the typewriter carriage and of rods 20 and 21 carried thereby. Rotatably and slidably mounted on the rod 20 is a denomination-selector 22, which may be held in proper letter-space positions therealong by means of a tooth 23 engaging notches in the rod 21, the selector 22 normally lying in depressed or ineffective position. Obviously, a plurality of selectors may be used.

Upon a letter-feeding movement of the carriage into a computing zone determined by one of the selectors, a frusto-conical roller 24 on the rear end of the selector 22 will ride up on the conical end of a roller 25, having a cylindrical portion of substantially the length of the computing zone, and cause a tappet 26 on the selector to engage seriatim the forward ends of jacks 27 of a certain set, to advance seriatim the usual pin-bars by connections (not shown). Provision is made of the usual jack-housing 28 and the usual housing 29 for the thrust-rods (not shown), by which the movements of the jacks 27 are transmitted to the computing mechanism, the housing 29 being connected to the jack-housing 28 at its forward end by any suitable means, such as ears 30, and the jacks and jack-housing being supported on the typewriter frame by any suitable means, such as a bar 29^a and brackets 29^b. There may be several sets of jacks, and actuation of a set of jacks by one selector 22 and not by others may be obtained by arranging the different sets with the forward ends of the jacks extending to different positions toward the front of the machine, and by arranging the tappets 26 on the different selectors 22 in accordance with the sets of jacks to be actuated thereby. The brackets 19 may also be utilized to support a toothed bar 31, on which may be positioned, at letter-space intervals, tabulator-stops 32 in position to be engaged by counter-stops 33, when the latter are lifted 60 by means (not shown). The computing

mechanism and the denomination-selecting mechanism, forming part thereof, may be, in general, similar to that disclosed in the patent to Richard M. Becker, No. 1,296,355, granted March 4, 1919.

Inasmuch as the present invention contemplates the use in a bookkeeping machine of the features of a continuous billing or so-called fan-fold machine, the axle 14 of the platen is journaled in ends 34 of a platen-lifting frame, said ends 34 being pivoted at the front of the platen on a rod 35, and being supported in normal position by arms 36, forming part thereof and resting on a rod 37, supported on the carriage 80 beneath the upper end of the rear paper-table 38. To insure the proper retention of the ends 34 in their normal positions, provision is made of means, including an arm 39, mounted on the rod 37 and having 85 on the front side thereof a hook 40, to engage over a pin 41 on the adjacent end 34 of the platen-lifting frame. The arm 39 may be limited in its forward movement by a lug 42 extending below the rod 37, so as 90 to engage a fixed part of the carriage when the arm 39 is in its forward position. Release of the platen-lifting frame may be effected by swinging the arm 39 to the rear by means of a finger-piece 43 at its upper 95 end.

Due to the projection of the jack-housing 28 above the platen, it is not feasible to use a horizontal carbon-carrier-track frame, as is usually the case in continuous billing or 100 fan-fold machines, since the webs or plies 44 would necessarily be bent downwardly over the front end of said frame or table and upwardly around the platen, even when the platen is in its raised position, and the friction between the webs and the carbon-sheets would be so great that the latter could not be retracted. According to this invention, the carbon-carrier-track or rearward extension 45 of the carriage 15 is mounted in 105 an inclined position, so that the webs 44, in passing over the track, will be inclined forwardly and downwardly, and pass to the elevated platen without bending down over the front end of the carbon-carrier-track frame or table. It will be evident that the carbon-sheets may be withdrawn even if the webs cannot be entirely straightened under the platen, the only requisite being that the bends in the webs and interleaved carbons must be reduced sufficiently to permit slipping of the carbon-sheets between the webs. The plane of the carbon-carrier-track frame or table may be substantially 110 tangential to the bottom of the displaced platen.

The rearward extension 45, which may be referred to in general as the carbon-carrier-track, comprises front and rear rods 46 and 47, respectively, connected by a plurality of 115 120 125 130

rods 48 on two of which, at opposite sides of the track, are mounted rails 49, the edges of which extend into grooves 50 in grooved rollers 51 mounted on a lower plate 52 of a carbon-carrier indicated in general by 53. Mounted on the plate 52 are the usual stepped blocks 53^a on which are supported blades 54, to which the carbon-sheets 55 are attached at their rear ends. For convenience in shifting the carbon-carrier on the rails 49, provision is made of a forwardly-extending arm 56 having at its end a finger-piece 57, which may easily be grasped by the operator and used for shifting the carbon-carrier 53. For reasons which will appear more clearly hereinafter, provision is made of leaf-springs 58 attached to the plate 52 near its forward edge and pressing against the rails 49, so as to resist accidental movement of the carbon-carrier along the track. To limit the movement of the carbon-carrier along the rails 49, provision may be made of a stop or stops 58^a.

At its rear, the extension 45 is supported by arms 59 depending from the outside rods 48, and each of the arms is provided with a roll 60 having a concave groove therearound to fit on a rail 61 which serves as a support therefor, engagement of the rail 61 by the rod being insured by an offset portion of each of the arms 59, extending beneath the rail 61 in such a manner as to prevent the lifting of the rolls 60 therefrom. Inasmuch as the typewriter frame 17 is supported by the computer casing 18, it is not feasible to support the rail 61 in the manner usual in continuous billing or fan-fold machines, and it has been found convenient to use brackets 62 attached to the typewriter frame at its back and near the sides thereof by suitable means, such as screws 63.

To support the extension 45 at its front end, suitable brackets 64 are attached to a bar 65 forming part of the carriage, and these brackets are provided at their upper ends, above the jack-housings, with recesses 66 to receive the reduced end or portions 67 of the front rod 46 of extension 45. It will be seen that the shoulders formed at the ends of the reduced portions 67 engage the inner faces of the brackets, thereby preventing relative movement, transverse to the machine, between the extension and the typewriter-carriage. One advantage of this arrangement resides in the fact that it permits the front end of the extension 45 to be swung upwardly, thereby making accessible the denomination-selecting mechanism normally lying therebeneath, so as to render it convenient to adjust the latter, when necessary.

To limit the upward movement of the front end of the extension 45 and to detain it in raised position when desired, a link 68 is pivoted at one end to the left-hand end of the

rod 46 and also by means of a pivot 68^a to one end of a link 69 mounted at its other end on a pivot or screw 70 carried by the left-hand bracket 64. Suitable provision may be made for lost motion at the pivot 68^a to avoid any interference with the upward swinging of the track 45. Upon lifting the forward end of the extension 45, the link 68, and, consequently, the link 69, will be shifted from the position shown in Figure 1 to the position shown in Figure 3, the link 69 then resting on a stop-pin 70^a carried by the left-hand bracket 64. In the normal position of the link 69, a lug 69^a forming a prolongation thereof beyond the pivot 70 engages the pin 70^a. If desired, provision may be made of a hook 71, which, when swung into position, will engage the shaft or rod 46 and prevent accidental displacement of the latter. It will be obvious that the leaf-springs 58 tend to maintain the carbon-carrier 53 in any position to which it has been moved during the movement of the extension 45 to and from the raised position shown in dot-and-dash lines, Figure 3.

When the machine is to be used, the platen-lifting frame is released by grasping the finger-piece 43 and swinging the arm 39 rearwardly. The lifting frame is then swung about the rod 35 until it assumes the position shown in Figure 3 and the webs 44, which have been passed over the rear rod 47, between the carbon-sheets 55 and over the front rod 46, are led beneath the platen and over a knife 72. The platen is then swung to its normal position to co-operate with feed-rolls 73 and the machine is ready for use. After typing a line on the webs, they may be advanced by operating the usual line-space mechanism, not shown. Such operation causes actuation of a gear 74, which, through a broad gear 75, actuates a gear 76 mounted on the end of the platen-axle. The line-spacing action, in printing on a set of forms such as are usually carried by the webs in use in the continuous billing machine, will advance the forward ends of the webs along a front paper-table 77, which forms part of the platen-lifting frame, and when the typing of a form has been completed, the lifting frame will again be swung to the Figure 3 position, and the leading ends of the webs grasped by the operator and drawn forward into contact with a gage 78 secured by a screw 79 at any desired position along a bar 80 forming an extension of the front paper-table 77. The operator, while holding the leading edges of the webs in gaged position, may grasp the finger-piece 57 with the other hand, and press the same rearwardly to shift the carbon-sheets 55 into position between unused portions of the webs. After restoring the platen to its mounted position and severing the used portions of the webs by drawing the same

across the knife 72, typing may be begun on another set of forms on the webs, and the operation described may be repeated as many times as required.

6. Inasmuch as the fan-fold mechanism whose use has just been described, is mounted, as herein disclosed, on a bookkeeping machine of the Underwood Hanson type, typing of digits may be accompanied by computation 10 in either one or both of the totalizers (not shown) associated with the two sets of jacks. The selectors 22 may be adjusted at suitable letter-space positions along the rod 20 by swinging them upwardly to withdraw their teeth 23 from the notches in the rod 21 and sliding them along the rod 20 to the desired positions. When such settings of the selectors 22 and of the tabulator-stops 32 are to be effected, the carbon-carrier-track 45 is 20 moved out of the way by swinging it to the raised position shown in dot-and-dash lines in Figure 3. When such settings have been made properly, the typing of digits and the corresponding computation may be effected 25 concomitantly during the passage of the carriage 15 through any computing zone determined by a selector 22.

Variations may be resorted to within the scope of the invention, and portions of the improvements may be used without others.

Having thus described my invention, I claim:

1. In combination, a typewriter-frame, a platen, a platen-carriage mounted to travel 25 on said frame, said carriage comprising a platen-lifting frame, a carbon-carrier, a web-table or carbon-carrier-track having, for the purpose specified, its forward end elevated above the platen, and being inclined forwardly and downwardly to enable webs extending through said carbon-carrier and between the elevated platen and the web-table to be straightened sufficiently to permit retraction by the carbon-carrier of carbon-sheets attached thereto, means to support the 40 rear end of the track to permit its front end to be swung upwardly and rearwardly, comprising a rail and rail-supporting brackets secured to the typewriter-frame at its back, and means on the carriage on which the forward end of the track rests when the carbon-carrier-track is in lowered position.

2. In combination, a typewriter-frame, a platen, a platen-carriage mounted to travel 55 on said frame, said carriage comprising a platen-lifting frame and a rear paper-table, a carbon-carrier, a carbon-carrier-track having, for the purpose specified, its forward end at an abnormal height above the platen, and being inclined forwardly and downwardly to enable webs extending through said carbon-carrier and between the platen and the rear paper-table to be straightened 60 sufficiently to permit retraction by the carbon-carrier, of carbon-sheets attached there-

to without excessive lifting of the platen, means to support the rear end of the track to permit it to be swung upwardly and rearwardly, the supporting means comprising a rail and rail-supporting brackets secured to 70 the typewriter-frame at its back, means on the carriage on which the forward end of the track rests when the carbon-carrier is in use, and a folding device connecting the carriage and the front end of the track, 75 whereby the upward movement of the carbon-carrier-track may be limited and the track maintained in raised position by the device when the latter is straightened in such upward movement of the track. 80

3. In combination, a typewriter-frame, a platen, a platen-carriage comprising a platen-lifting frame and a rear paper-table, a carbon-carrier, a carbon-carrier-track comprising a front rod, means to support the 85 rear end of the track including a rail, a connection between the track and the rail whereby the former may be swung about the latter, and brackets extending upwardly from the back of the typewriter-frame and provided with recessed upper ends to receive reduced portions of the front rod when the track is swung downwardly to its position for use, and thereby effect a connection 90 between the carriage and the track to cause 95 the track to travel with the carriage.

4. In combination, a typewriter-frame, a platen, a platen-carriage mounted to travel on said frame and comprising a platen-lifting frame and a rear paper-table, a carbon-carrier, a carbon-carrier-track supported at 100 its rear for movement transverse with respect to the machine, and to enable the front end thereof to be swung upwardly, and provisions on the carriage and the forward end 105 of the carbon-carrier-track whereby the latter, when in normal position, will be connected with the carriage to travel therewith.

5. In combination, a typewriter-frame, a platen, a platen-carriage mounted to travel 110 on said frame and comprising a platen-lifting frame and a rear paper-table, a carbon-carrier, a carbon-carrier-track supported at its rear for movement transverse with respect to the machine, and to enable the front 115 end thereof to be swung upwardly, provisions on the carriage and the forward end of the carbon-carrier-track whereby the latter, when in normal position, will be connected with the carriage to travel therewith, 120 and latching means to hold the forward end of the carbon-carrier-track against upward movement relative to the carriage.

6. In combination, a typewriter-frame, a platen, a platen-carriage mounted to travel 125 on said frame and comprising a platen-lifting frame and a rear paper-table, a carbon-carrier, a carbon-carrier-track supported at its rear for movement transverse with respect to the machine, and to enable the front 130

end thereof to be swung upwardly, provisions on the carriage and the forward end of the carbon-carrier-track whereby the latter, when in normal position, will be connected with the carriage to travel therewith, and means to limit the upward movement of the carbon-carrier-track to detain it in its raised position.

7. In combination, a typewriter-frame, a platen, a platen-carriage mounted to travel on said frame, said carriage comprising a platen-lifting frame and a rear paper-table, a carbon-carrier, a carbon-carrier-track inclined forwardly and downwardly to enable webs extending through said carbon-carrier and between the platen and the rear paper-table to be straightened sufficiently to permit retraction by the carbon-carrier of carbon-sheets attached thereto, without excessive lifting of the platen, and supporting means for the track permitting the forward end thereof to be swung upwardly from the carriage.

8. In combination, a typewriter-frame, a platen, a platen-carriage mounted to travel on said frame, said carriage comprising a platen-lifting frame and a rear paper-table, a carbon-carrier, a carbon-carrier-track inclined forwardly and downwardly to enable webs extending through said carbon-carrier and between the platen and the rear paper-table to be straightened sufficiently to permit retraction by the carbon-carrier of carbon-sheets attached thereto without excessive lifting of the platen, supporting means for the track permitting the forward end thereof to be swung upwardly from the carriage, and means to hold the track in its normal position.

40 9. In combination, a typewriter-frame, a platen, a platen-carriage mounted to travel on said frame, said carriage comprising a platen-lifting frame and a rear paper-table, a carbon-carrier, a carbon-carrier-track inclined forwardly and downwardly to enable webs extending through said carbon-carrier and between the platen and the rear paper-table to be straightened sufficiently to permit retraction by the carbon-carrier of carbon-sheets attached thereto without excessive lifting of the platen, supporting means for the track permitting the forward end thereof to be swung upwardly from the carriage, and means to hold the track in its raised position.

55 10. In combination, a typewriter-frame, a platen, a platen-carriage mounted to travel on said frame, said carriage comprising a platen-lifting frame and a rear paper-table, a carbon-carrier, a carbon-carrier-track inclined forwardly and downwardly to enable webs extending through said carbon-carrier and between the platen and the rear paper-table to be straightened sufficiently to permit retraction by the carbon-carrier of carbon-

sheets attached thereto without excessive lifting of the platen, supporting means for the track permitting the forward end thereof to be swung upwardly from the carriage, and means to limit upward movement of the track and to hold it in raised position.

11. In combination, a typewriter-frame, a platen, a platen-carriage mounted to travel on said frame, said carriage comprising a platen-lifting frame and a rear paper-table, a carbon-carrier, a carbon-carrier-track inclined forwardly and downwardly to enable webs extending through said carbon-carrier and between the platen and the rear paper-table to be straightened sufficiently to permit retraction by the carbon-carrier of carbon-sheets attached thereto without excessive lifting of the platen, and supporting means for the track including a rail on which the track is mounted for travel with the carriage and for swinging movement for separating the front end of the track from the carriage.

12. In combination, a typewriter-frame, a platen, a platen-carriage mounted to travel on said frame, said carriage comprising a platen-lifting frame and a rear paper-table, a carbon-carrier, a carbon-carrier-track inclined forwardly and downwardly to enable webs extending through said carbon-carrier and between the platen and the rear paper-table to be straightened sufficiently to permit retraction by the carbon-carrier of carbon-sheets attached thereto, without excessive lifting of the platen, supporting means for the track including a rail on which the track is mounted for travel with the carriage and for swinging movement for separating the front end of the track from the carriage, and a projection-and-recess connection between the track and the carriage whereby, when the front end of the track is swung into engagement with the carriage, it will be connected with the carriage to travel therewith.

13. In combination, a typewriter-frame, a platen, a platen-carriage mounted to travel on said frame, said carriage comprising a platen-lifting frame and a rear paper-table, a carbon-carrier, a carbon-carrier-track having its forward end at a considerable height above the platen, for the purpose specified, and being inclined forwardly and downwardly to enable webs extending through said carbon-carrier and between the platen and the rear paper-table to be straightened sufficiently to permit retraction by the carbon-carrier of carbon-sheets attached thereto without excessive lifting of the platen, which would otherwise be necessary, due to the abnormal elevation of the forward end of the carbon-carrier-track, and braking means to prevent accidental movement of said carbon-carrier on its track.

14. In a combined typewriting and computing machine, in combination, a type-

- writer-frame, a platen, a platen-carriage mounted to travel on the frame, said carriage comprising a platen-lifting frame and a rear paper-table, computing mechanism including denomination-selecting mechanism mounted on the typewriter-frame adjacent the upper edge of the rear paper-table and at a considerable elevation above the platen, and a computer casing on which the typewriter frame rests, a carbon-carrier, a carbon-carrier-track inclined forwardly and downwardly over the denomination-selecting mechanism so as to enable webs extending through the carbon-carrier to be straightened beneath the platen, when the latter is lifted, to permit retraction by the carbon-carrier of the carbon-sheets attached thereto, means to support the rear end of the track comprising a rail and rail-supporting brackets secured to the back of the typewriter-frame, and provisions on the carriage and the forward end of the track whereby the track will be caused to travel with the carriage.
- 15 15. In combination, a typewriter-frame, a platen, a platen-carriage mounted to travel on said frame and comprising a platen-lifting frame and a rear paper-table, computing mechanism including denomination-selecting mechanism adjacent the upper edge of the rear paper-table and at a considerable elevation above the normal position of the platen, a carbon-carrier, and a carbon-carrier-track inclined forwardly and downwardly over the denomination-selecting mechanism to enable webs extending through the carbon-carrier to be straightened sufficiently to permit retraction by the carbon-carrier of carbon-sheets attached thereto without excessive lifting of the platen.
- 20 16. In combination, a typewriter-frame, a platen, a platen-carriage mounted to travel on said frame and comprising a platen-lifting frame and a rear paper-table, computing mechanism including denomination-selecting mechanism adjacent the upper edge of the rear paper-table, a carbon-carrier, a carbon-carrier-track inclined forwardly and downwardly over the denomination-selecting mechanism to enable webs extending through the carbon-carrier to be straightened sufficiently to permit retraction by the carbon-carrier of carbon-sheets without excessive lifting of the platen, and track-supporting means permitting the track to be swung upwardly to render the denomination-selecting mechanism accessible.
- 25 17. In combination, a typewriter-frame, a platen, a platen-carriage mounted to travel on said frame, said carriage comprising a platen-lifting frame and a rear paper-table, a carbon-carrier, a carbon-carrier-track, inclined forwardly and downwardly, to enable webs extending through said carbon-carrier and between the platen and the rear paper-table to be straightened sufficiently to permit retraction by the carbon-carrier of carbon-sheets attached thereto without excessive lifting of the platen, means to support the rear end of the track, comprising a rail and rail-supporting brackets secured to the typewriter-frame at its back, means on the carriage on which the forward end of the track rests when the carbon-carrier is in use, and a collapsible device connecting the carriage and the forward end of the track to limit the upward movement of the track, and, when extended, to maintain the track in raised position.
- 30 18. In a combined typewriting and computing machine, in combination, a typewriter-frame, a platen, a platen-carriage mounted on said frame and comprising a platen-lifting frame and a rear paper-table, computing mechanism mounted on the rear of the typewriter-frame and extending above the upper edge of the rear paper-table, a carbon-carrier, a carbon-carrier-track, means to support the rear end of the track including a rail and connections between the track and the rail to enable the former to be swung about the latter, brackets extending from the back of the typewriter-frame upwardly to the top of the computing mechanism, and provisions on the upper ends of the brackets and the forward end of the track whereby the track, when swung downwardly to engage the brackets, will be connected with the carriage to travel therewith.
- 35 19. In a combined typewriting and computing machine, in combination, a typewriter-frame, a platen, a platen-carriage mounted to travel on said frame and comprising a platen-lifting frame and a rear paper-table, computing mechanism mounted on the typewriter-frame adjacent the upper edge of the rear paper-table, a carbon-carrier, a carbon-carrier-track extending upwardly and rearwardly over the computing mechanism and supported at its rear for movement transverse with respect to the machine and to enable the forward end thereof to be swung upwardly to expose said computing mechanism, and provisions on the carriage and the forward end of the carbon-carrier-track whereby the latter, when in normal position, will be connected with the carriage to travel therewith.
- 40 20. In combination, a typewriter-frame, a platen, a platen-carriage mounted to travel on said frame and comprising a platen-lifting frame and a rear paper-table, a carbon-carrier, a carbon-carrier-track supported at its rear for movement across the machine and to enable the forward end thereof to be swung upwardly, and braking means to prevent accidental movement of said carbon-carrier on its track.
- 45 21. In a combined typewriting and computing machine, in combination, a type-

- writer-frame, a platen, a platen-carriage mounted to travel on said frame and comprising a platen-lifting frame and a rear paper-table, a set of denominational jacks on 5 the typewriter-frame at the rear of said paper-table, a denomination-selector adjustable along said carriage at the rear of said paper-table to co-operate with said jacks and to determine computing zones for said carriage, a carbon-carrier, and a carbon-carrier-track extending upwardly and rearwardly over the set of jacks and supported at its rearward end for movement across the machine and for an upward swinging of the 10 front end thereof to enable the denomination-selector to be set in any desired letter-space position on said carriage.
22. In a combined typewriting and computing machine, in combination, a typewriter-frame, a platen, a platen-carriage comprising a platen-lifting frame and a rear paper-table, computing mechanism including a set of jacks mounted on the rear of the typewriter-frame adjacent the upper edge 15 of the rear paper-table, and a selector adjustable along said carriage to engage said jacks and determine the computing zones for the carriage, a carbon-carrier, and a carbon-carrier-track extending downwardly and 20 forwardly over said jacks and supported for swinging movement away from said jacks to permit the selector to be set in any desired letter-space position on the carriage.
23. In a typewriting machine, for the purpose specified, in combination, a cylindrical platen displaceable upwardly to permit webs in the machine to be straightened thereunder, a carbon-carrier to retract carbons interleaved between said webs, and a 25 carbon carrier-support having its forward end in its normal position elevated substantially above the normal position of the platen, as set forth, and being inclined forwardly and downwardly to bring its plane 30 substantially tangential to the bottom surface of the elevated platen, to permit the webs to be straightened under the platen when the latter is displaced, without bending down over the front of the carbon-carrier-support.
24. A machine for typing upon superposed plies of a web, comprising a revoluble platen and a platen-carriage, said platen mounted upon a frame upon said carriage 35 for displacement of the platen upwardly to straighten out the web to permit the shifting of carbons, said machine also having in rear thereof mechanism to co-operate with the carriage of which mechanism certain parts 40 are elevated substantially above the platen, a web-table extending rearwardly from the carriage, and a carbon-carrier movable along said table, said web-table connected to said platen-carriage to travel over said elevated parts, the carbon-carrier movable rearward- 45
- ly along the web-table for shifting the carbons along the web, said web-table and said platen-displacing frame so mounted and operating that when the platen is in its elevated position, the bottom surface thereof 50 lies substantially in the plane of said web-table, to permit the web extending forwardly from said table to run to the bottom of the platen in a substantially straight condition, without bending down over the front 55 edge of the web-table, to permit the shifting of the carbon-sheets along the web.
25. A machine for typing upon superposed plies of web, comprising a typewriter frame, a platen, a platen-carriage mounted 60 to travel along said frame, said carriage comprising a frame upon which the platen may be displaced upwardly for straightening out the web to permit the carbons to be shifted between the plies of web, a carbon-carrier, and a carbon-carrier supporting and guiding table connected to the carriage to travel therewith, the forward end of said table being at the rear of the platen and at a 65 substantially higher elevation than the 70 platen, to clear elevated stationary parts at the rear of the typewriting machine which co-operate with the carriage, as set forth, the web running forwardly over the carbon-carrier, and bending down around the front 75 of said table and under the platen to feed up in front thereof, said platen when in its elevated position being below the front of 80 said table, and the latter being inclined rearwardly and upwardly from its front end, so that the plane of the inclined table is about tangential to the bottom surface of the platen when in elevated position, to permit the web to run off from the table to the bottom of the platen, without being bent down around the front edge of said table, thereby 85 to permit the web to be straightened out sufficiently to permit the shifting of the carbon-sheets between the plies of web.
26. A machine for typing upon superposed plies of web, comprising a typewriter frame, a platen, a platen-carriage mounted 90 to travel along said frame, said carriage comprising a frame upon which the platen may be displaced upwardly for straightening out the web to permit the carbons to be shifted between the plies of web, a carbon-carrier, a carbon-carrier supporting and guiding table connected to the carriage to travel therewith, the forward end of said table being at the rear of the platen and at a 95 substantially higher elevation than the platen, to clear elevated stationary parts at the rear of the typewriting machine which co-operate with the carriage, as set forth, the web running forwardly over the carbon-carrier, and bending down around the front 100 of said table and under the platen to feed up in front thereof, said platen when in its elevated position being below the front of said table, and the latter being inclined rearwardly and upwardly from its front end, so that the plane of the inclined table is about tangential to the bottom surface of the platen when in elevated position, to permit the web to run off from the table to the bottom of the platen, without being bent down around the front edge of said table, thereby 105 to permit the web to be straightened out sufficiently to permit the shifting of the carbon-sheets between the plies of web.
27. A machine for typing upon superposed plies of web, comprising a typewriter frame, a platen, a platen-carriage mounted 110 to travel along said frame, said carriage comprising a frame upon which the platen may be displaced upwardly for straightening out the web to permit the carbons to be shifted between the plies of web, a carbon-carrier, a carbon-carrier supporting and guiding table connected to the carriage to travel therewith, the forward end of said table being at the rear of the platen and at a 115 substantially higher elevation than the platen, to clear elevated stationary parts at the rear of the typewriting machine which co-operate with the carriage, as set forth, the web running forwardly over the carbon-carrier, and bending down around the front 120 of said table and under the platen to feed up in front thereof, said platen when in its elevated position being below the front of said table, and the latter being inclined rearwardly and upwardly from its front end, so that the plane of the inclined table is about tangential to the bottom surface of the platen when in elevated position, to permit the web to run off from the table to the bottom of the platen, without being bent down around the front edge of said table, thereby 125 to permit the web to be straightened out sufficiently to permit the shifting of the carbon-sheets between the plies of web.
28. A machine for typing upon superposed plies of web, comprising a typewriter frame, a platen, a platen-carriage mounted 130 to travel along said frame, said carriage comprising a frame upon which the platen may be displaced upwardly for straightening out the web to permit the carbons to be shifted between the plies of web, a carbon-carrier, a carbon-carrier supporting and guiding table connected to the carriage to travel therewith, the forward end of said table being at the rear of the platen and at a substantially higher elevation than the platen, to clear elevated stationary parts at the rear of the typewriting machine which co-operate with the carriage, as set forth, the web running forwardly over the carbon-carrier, and bending down around the front of said table and under the platen to feed up in front thereof, said platen when in its elevated position being below the front of said table, and the latter being inclined rearwardly and upwardly from its front end, so that the plane of the inclined table is about tangential to the bottom surface of the platen when in elevated position, to permit the web to run off from the table to the bottom of the platen, without being bent down around the front edge of said table, thereby to permit the web to be straightened out sufficiently to permit the shifting of the carbon-sheets between the plies of web.

- front of said table, and the latter being inclined rearwardly and upwardly from its front end, so that the plane of the inclined table is about tangential to the bottom surface of the platen when in elevated position, to permit the web to run off from the table to the bottom of the platen, without being bent down around the front edge of said table, thereby to permit the web to be straightened out sufficiently to permit the shifting of the carbon-sheets between the plies of web, and means to overcome the tendency of the carbon-carrier to slide down along the inclined table.
27. In a front-strike typewriting machine, a carriage, and a revoluble platen displaceable upwardly in the carriage sufficiently to straighten out the work-sheets to permit car-

bons to be shifted back along the web, said machine comprising adding mechanism having parts to co-operate with the carriage, said co-operating parts mounted at the rear of the carriage and above the level of the platen when the latter is in typing position, a carbon-carrier, and a track therefor connected to and extending backwardly from the type-writer carriage, said track being above said adding-machine mechanism, and extending in a direction substantially tangential to the bottom of the platen when the latter is displaced upwardly for so straightening out the work-sheets.

BURNHAM C. STICKNEY.
